COMBINED CASING, MIRROR, AND LIPSTICK

Harold H. Thornton, New York, N. Y.

Application February 23, 1950, Serial No. 8,073

Term of patent 7 years

(Cl. D86—10)

To all whom it may concern:

Be it known that I, Harold H. Thornton, a citizen of the United States, residing at 108 West 85th Street, in the county of New York and State of New York, have invented a new, original, and ornamental Design for a Combined Casing, Mirror, and Lipstick, of which the following is a specification, reference being had to the accompanying drawing, constituting a part hereof.

Fig. 1 is a perspective view of a combined casing, mirror, and lipstick, showing my new design, all parts being shown in closed position;

Fig. 2 is a perspective view similar to Fig. 1, but showing the mirror portion and the lipstick in position for use;

Fig. 3 is a front perspective of the article as shown in Fig. 2; and

Fig. 4 is a fragmentary perspective view showing the right end of the article in respect to Fig. 1.

I claim:

The ornamental design for a combined casing, mirror, and lipstick, substantially as shown.

HAROLD H. THORNTON.
